UNITED STATES PATENT OFFICE.

JOHN C. ST. JOHN, OF BOSTON, MASSACHUSETTS, ASSIGNOR, BY DIRECT AND MESNE ASSIGNMENTS, TO IMPROVED PIN TICKET COMPANY, A CORPORATION OF MASSACHUSETTS, 1912.

PIN-TICKET.

1,049,167.

Specification of Letters Patent.

Patented Dec. 31, 1912.

Application filed June 10, 1912. Serial No. 702,648.

To all whom it may concern:

Be it known that I, JOHN C. ST. JOHN, a citizen of the United States, residing at Roxbury, Boston, in the county of Suffolk 5 and State of Massachusetts, have invented new and useful Improvements in Pin-Tickets, of which the following is a specification.

This invention relates to pin tickets such 10 as are used on clothing and generally on articles of merchandise for indicating the name of the dealer, prices and sizes of the articles to which the pin ticket is attached, and any other information that may be 15 necessary.

The object of the invention is to provide 20 a pin ticket which is simple and cheap in its construction, which can be readily attached to the articles of merchandise and 25 which may be attached to the clothing in such a manner that it will not become accidentally detached therefrom, and, furthermore to produce a pin ticket of the character set forth which, when attached to 30 articles of merchandise, shall have the free end of the pin so guarded that the same will not injure the article to which it is attached and will not injure persons handling 35 said article, and which is also so constructed that when a number of such articles, with said pin tickets attached thereto, are placed one upon the other in a pile, the free end of the pin cannot stick into or injure in any way the article adjacent thereto to which 40 it is not attached.

The invention consists in a pin ticket constructed as hereinafter described and particularly as set forth in the claim.

Referring to the drawings: Figure 1 is 45 a rear elevation of a pin ticket embodying my invention. Fig. 2 is a sectional elevation taken on line 2—2 of Fig. 1, looking toward the left in said figure. Fig. 3 is a front elevation of my improved pin ticket 50 showing the same attached to a piece of fabric. Fig. 4 is a sectional elevation taken on line 4—4 of Fig. 3. Fig. 5 is a front elevation of a modified form of my improved pin ticket. Fig. 6 is a sectional elevation 55 taken on line 6—6 of Fig. 5.

Like numerals refer to like parts throughout the several views of the drawings.

In the drawings, 10 is a piece of sheet material, preferably cardboard, and constituting a tag.

11 is a pin formed of flexible wire, preferably bent at one end as at 12 and attached at that end to the cardboard 10 by means of a strip 13 of sheet material, such as paper, said paper being attached to the reverse face of the cardboard by suitable adhesive material such as paste or glue 9. A hole 14 extends through the cardboard 10 from the obverse to the reverse face thereof and the pin 11 extends along the reverse 60 face of the cardboard 10, across the hole 14 and beyond the edge 15 of the tag 10. The hole 14 is preferably located adjacent to the edge 15 and the pin 11 is of such a length that its free end extends beyond the edge 15 65 to such an extent that said free end may be bent around the edge 15 and along the obverse face of the cardboard, terminating in the hole 14, as illustrated in Figs. 3 and 4.

Figs. 1 and 2 illustrate the pin ticket 70 before it is attached to the fabric.

In Figs. 3 and 4 the pin ticket is illustrated as attached to a piece of fabric 16.

To attach the pin ticket hereinbefore 75 specifically described and illustrated in Fig. 1 and 2 to a piece of fabric 16, the free end of the pin 11 is inserted through or into the fabric 16 for a certain portion of its length and then brought out of the fabric with that face thereof adjacent to the reverse face of the pin ticket lying thereagainst. Said free end is then bent around the edge 15 along the obverse face of the tag 10, and is bent into the hole 14, its extreme free end terminating within said hole, 80 as clearly illustrated in Fig. 4. It will be evident that when the pin ticket is thus attached to the fabric, it is firmly locked thereto and cannot become accidentally detached therefrom and also that the point of 85 the pin being within the hole 14 and between the obverse and reverse faces of the tag will be guarded so that it will not stick into other fabric adjacent to the obverse face of the tag and also so that it will not 90 stick into the hands of the person handling the fabric with the ticket thereon.

In Figs. 5 and 6 I have illustrated a modified form of my invention in which the tag 17 of cardboard has a hole 18 therein and the pin 19 is bent into a U-shape at 20 extending through the cardboard from the reverse to the obverse face and then back again from the obverse to the reverse face and thence the pin extends along the reverse 105 110

face of the tag and beyond the edge 21. The ticket in this form is used as in the form illustrated in Figs. 1 to 4 inclusive, by bending the free end of the pin around the edge 21 and into the hole 18.

It is evident that the pin in either case must extend at its free end beyond the edge about which it is to be bent to such an extent that when bent, as described, said free end will project into the hole 14 or 18, as the case may be.

Having thus described my invention, what I claim and desire by Letters Patent to secure is:

15 A pin ticket consisting of a tag of sheet material having a hole extending entirely

therethrough from its obverse to its reverse face, a pin of flexible wire fast at one end thereof to said tag and extending along one face of said tag across said hole with its free end extending beyond one edge of said tag to an extent greater than the shortest distance from said hole to said edge, whereby said free end may be bent around said edge and into said hole.

25 In testimony whereof I have hereunto set my hand in presence of two subscribing witnesses.

JOHN C. ST. JOHN.
